UNITED STATES PATENT OFFICE.

IGNACY WROBLEWSKI, OF KRAKOW, AUSTRIA-HUNGARY.

CASEMENT-WINDOW.

No. 851,725.

Specification of Letters Patent.

Patented April 30, 1907.

Application filed September 6, 1906. Serial No. 333,504.

To all whom it may concern:

Be it known that I, IGNACY WROBLEWSKI, a subject of the Emperor of Austria, and a resident of Krakow, Province of Galicia, 5 Austria-Hungary, have invented certain new and useful Improvements in Casement-Windows, of which the following is a specification, accompanied by drawings.

This invention relates to improvements in 10 French or casement windows, more particularly to that class of windows which open inwardly and in which the sashes are pivotally and vertically movable.

The objects of the invention are to improve 15 upon the construction and operation of such windows and enable the sashes to be more readily raised and lowered and maintained in any desired position.

Further objects of the invention will hereinafter appear and to these ends the invention consists of means for carrying out the above objects embodying the features of construction, combinations of elements and arrangement of parts having the general mode 25 of operation substantially as hereinafter fully described and claimed in this specification and shown in the accompanying drawings, in which,—

Figure 1 is a side elevation of a window 30 embodying the invention; Fig. 2 is an enlarged transverse sectional detail plan view, taken through the meeting rails of the window sashes on the line 2—2 of Fig. 1, looking in the direction of the arrows; Fig. 3 is an enlarged detail sectional plan view on the line 3—3 of Fig. 1, looking in the direction of the arrows; Fig. 4 is an enlarged detail vertical sectional view on the line 4—4 of Fig. 1, looking in the direction of the arrows; Fig. 5 40 is an enlarged detail vertical sectional view on the line 5—5 of Fig. 1, looking in the direction of the arrows; Fig. 6 is an enlarged detail transverse vertical sectional view on the line 6—6 of Fig. 1, looking in the direction of the arrows; Fig. 7 is an enlarged detail side elevation of one of the lifting devices with the casing removed; Fig. 8 is an enlarged detail front view of one of the 45 hinges; Fig. 9 is a detail front view of the hinge partly in section; Fig. 10 is a transverse end view of one of the raising and lowering devices.

Referring to the drawings, A represents the window sill and B the top rail of the window 50 frame, while C represents the side rails of the window frame. The window sashes are piv-

otally and vertically movable in the window frame, and in this instance a double window is shown, although the invention is equally applicable to single windows or doors. The 60 side rails D of the window sashes are suitably pivoted to the frame C, in this instance the frame being provided with sockets E, while the side rails of the window sashes are provided with projecting hooks or pivot pins F, 65 which seat in the sockets E and are vertically movable therein. Preferably the apertures in the sockets E slant inwardly and the pivots F slant inwardly, so that when one of the sashes is raised the side rail D is moved 70 away from the frame C, and the pivot pin F takes the position shown in Fig. 9 of the drawings. As the sash is lowered the pivot pin takes the position shown in Fig. 8, thereby drawing the sash tightly against the frame 75 of the window.

Interlocking dust, air and waterproof connections are provided preferably on all sides of the window between the sash and the frame. As shown, the window sill A is 80 grooved along its length at G, and the lower sash rail is also grooved at I. The tongue or projection J on the lower sash rail enters the groove G in the window sill when the sash is in lowered position, and the outer tongue or 85 projection K of the lower sash rail is seated outside of and below the upper and outer edge of the window sill, as shown in sectional view in Fig. 4 when the sash is in lowered position. Preferably the grooves G and I are 90 slightly deeper than the tongues which co-operate therewith, so that air spaces are left between the tongues and the bottoms of the grooves. According to the construction described a secure air and water tight joint is 95 formed. The top sash rail L is adapted to slide vertically inside of the upper rail B of the window frame, and sufficient space is provided between the top of the sash rail L and the rail B to permit vertical movement. 100

In order to open the window one wing or sash is lifted sufficiently on its hinges without disconnection thereof to unlock it from the other wing or sash and from the casing, and then swung horizontally on its pivots. 105 The other wing or sash is likewise unlocked by a lift and then swung open. The sashes are closed in the reverse order and lowered into locked position after being swung shut.

Means are provided for thus raising the window sashes to unlock and lock them, which means are simple in construction, safe 110

2
in operation, compact in structure and symmetrical in appearance. The lifting and lowering mechanism herein shown comprises a small bracket or box O secured to the inner face of the window casing and a plate or bracket W secured to the inner face of the sash. The sash bracket W is provided with two elongated lugs W' and W'', forming a forked projection at right angles to the plane of the sash. A lever R having a central slot R' is pivoted at one end within the box on a stud S and provided at the other end with a projecting tongue R'' which engages the forked projection of the sash plate W at the outer ends of the elongated lugs W' and W''. The elongation of the lugs enables the sash to swing toward or around the end of said tongue without interference therewith. The tongue R'' is rounded as shown in Fig. 7, and thereby forms in its different positions a close connection with the sides of the fork avoiding lost motion and providing a compact construction.

A shaft P is journaled in the box O at right angles to the window frame. This shaft is provided within the box with a cam or eccentric P' which engages the slot of the lever R for lifting or lowering the sash. A crank P'' which may have an angular or other locking connection with the shaft P serves to turn said shaft a half rotation in one direction to swing said lever upward to lift and disengage the sash and a half rotation in the opposite direction to swing said lever downward to lower and lock the sash. The crank swings in a plane parallel with the plane of the window frame and may be readily applied for lifting and lowering the sash. One crank may serve the purpose for any two or more sashes.

The box or bracket O is preferably provided with a removable cover shown in position in Fig. 1, said cover being removed in Fig. 7. This cover substantially conceals the lifting mechanism and prevents dust and dirt from entering the box and interfering with the bearings of the lifting devices. In this construction the lifting mechanism is very compact and serves to hold the window sash when being raised or lowered, preventing sudden jars in the lowering thereof which would tend to break the glass.

The side rails D of the window sashes interlock with the side rails C of the frame as shown in Fig. 3 by tongue and groove connections, and the meeting rails Y of the sashes overlap as shown in Fig. 2 to form a weather tight connection. Preferably spaces Z are left between the meeting faces of the sash rails Y to permit side movement of the sashes.

Means are provided for drawing the window sash or sashes tightly against the frame when the window is closed. In this instance the upper rail L of one of the sashes is lowered at a for the reception of an upwardly

turned hook b which hook is secured to the upper rail B of the frame. An apertured plate c secured to the rail L over the recess a is adapted to co-operate with the hook b, and engages over said hook when the window is closed and lowered. As shown, the hook b is provided with a vertical front face d and an inner face e which slants toward the upper rail B of the window frame so that when the window sash is closed and lowered, bringing the aperture in the plate c over the hook d, the sash is drawn against the window frame and tightly held in position. When the sash is raised the plate c is released from engagement with the hook d to permit the window to be opened.

Preferably interlocking connections are provided between the meeting rails of the window sashes to hold said rails together when the window is closed. As shown, the meeting faces of the rails Y are suitably recessed to receive the interlocking hooks f and g which engage when the window is closed and each sash is in lowered position.

According to the construction disclosed, the window cannot stick and then drop suddenly and thus break the glass, but a constant even movement is obtained in both raising and lowering the window and the sashes may be maintained in any desired position.

It will also be seen that the raising and lowering devices are situated conveniently at each side of the window, and the handles P extend substantially parallel with the side rails C of the frame when in raised or lowered position so that there is no danger that these handles will interfere with or break the window panes when the window is opened.

Obviously some features of this invention may be used without others and the invention may be embodied in widely varying forms.

Therefore, without limiting the invention to the devices shown and described, and without enumerating equivalents, I claim and desire to obtain by Letters Patent the following:

1. In a casement window the combination of a window frame, a vertically movable window sash hinged to swing on said frame, and means for lifting and lowering said sash for unlocking and locking it, comprising a bracket attached to a side rail of said sash and provided with elongated lugs projecting from the face thereof, a box secured to a side rail of said window frame adjacent to said bracket, a slotted lever pivoted at one end within said box and provided at its other end with a projecting rounded tongue which extends between the outer ends of the elongated lugs of said sash bracket leaving a clearance which permits the bracket to swing freely around the end of said tongue, a shaft pivoted within said box at right angles to the

plane of said window frame and provided with a cam engaging the slot of said lever, and means for turning said shaft to unlock or lock said sash.

- 5 2. In a casement window the combination of a window frame, a vertically movable window sash hinged to swing on said frame, and means for lifting and lowering said sash for unlocking and locking it, comprising a 10 bracket attached to a side rail of said sash and provided with elongated lugs projecting from the face thereof, a box secured to a side rail of said window frame adjacent to said bracket, a slotted lever pivoted at one end within said box and provided at its other end 15 with a projecting rounded tongue which ex-

tends between the outer ends of the elongated lugs of said sash bracket to swing freely around the end of said tongue, a shaft pivoted within said box at right angles to the 20 plane of said window frame and provided with a cam engaging the slot of said lever, and detachable means for turning said shaft to unlock or lock said sash.

In testimony whereof I have signed this 25 specification in the presence of two subscribing witnesses.

IGNACY WROBLEWSKI.
